DESIGN FOR A LAMP OR SIMILAR ARTICLE

Leon Lewkowicz and Ernest F. Bennett,
New York, N. Y.

Application October 22, 1948, Serial No. 149,253

Term of patent 14 years

(Cl. D48—20)

To all whom it may concern:

Be it known that we, Leon Lewkowicz and Ernest F. Bennett, citizens of no country, residing at city, county, and State of New York, have invented a new, original, and ornamental Design for a Lamp or Similar Article, of which the following is a specification, reference being had to the accompanying drawing, forming part thereof.

In the drawing

Fig. 1 is a front elevational view of a lamp or similar article showing our new design;

Fig. 2 is a side elevational view of the lamp shown in Fig. 1;

Fig. 3 is a rear elevational view thereof;

Fig. 4 is a top plan view thereof;

Fig. 5 is a bottom plan view thereof; and

Fig. 6 is a vertical section of the lamp housing along the lines 6—6 of Fig. 1.

We claim:

The ornamental design for a lamp or similar article, as shown.

LEON LEWKOWICZ.
ERNEST F. BENNETT.
